[57] CLAIM

The ornamental design for a golf case, as shown and described.

DESCRIPTION

FIG. 1 is a rear elevational view of a golf case with the upper grip in extended position showing my new design;

FIG. 2 is a right side elevational view thereof;

FIG. 3 is a front elevational view thereof;

FIG. 4 is a top plan view thereof;

FIG. 5 is a bottom plan view thereof;

FIG. 6 is a bottom plan view of the golf case in open position.

In the views of FIGS. 1 to 3, the upper grip is pulled out of its retracted position.

FIG.3

FIG.2

FIG.1
